UNITED STATES PATENT OFFICE.

CHRIS SILBER, OF MERIDEN, CONNECTICUT, ASSIGNOR TO INTERNATIONAL SILVER CO., OF SAME PLACE.

DESIGN FOR A HANDLE FOR SPOONS, FORKS, OR SIMILAR ARTICLES.

SPECIFICATION forming part of Design No. 34,774, dated July 16, 1901.

Application filed June 21, 1901. Serial No. 65,509. Term of patent 7 years.

To all whom it may concern:

Be it known that I, CHRIS SILBER, of Meriden, in the county of New Haven and State of Connecticut, have invented and produced 5 a new and useful Design for a Handle for Spoons, Forks, or Similar Articles; and I do hereby declare the following, when taken in connection with the accompanying drawing and the letters of reference marked thereon, 10 to be a full, clear, and exact description of the same, and which said drawing constitutes part of this specification and represents a face view of a handle embodying my design.

This invention relates to a design for a handle for spoons, forks, and similar articles; and the design consists in a handle having 15 the ornamentation hereinafter described, and shown in the accompanying illustration.

The central face of the handle is a panel 20 A, which extends substantially throughout the length of the handle. This panel is bor-

dered on opposite sides by long scrolls B, which extend from small foliated scrolls C at the inner end to larger scrolls D, which expand to form the tip of the spoon, the central portion of which is formed by a double scroll E. Above the center of the handle the sides are expanded and ornamented with fine scrolls F, all as shown in the accompanying illustration. 25

I claim—

The design for a handle for spoons, forks and similar articles as herein shown and described.

In testimony whereof I have signed this 35 specification in the presence of two subscribing witnesses.

CHR. SILBER.
